UNITED STATES PATENT OFFICE.

IRVING LEWIS HAWKINS, OF WINDSOR, NEW YORK.

DEVICE FOR OVERCOMING DEAD-CENTERS AND FOR CONVERTING MOTION.

SPECIFICATION forming part of Letters Patent No. 298,199, dated May 6, 1884.

Application filed February 20, 1884. (No model.)

To all whom it may concern:

Be it known that I, I. L. HAWKINS, a citizen of the United States, residing at Windsor, in the county of Broome and State of New York, have invented certain new and useful improvements in machinery attachments, which overcome the dead-point, also for changing power from rotary to reciprocal and reciprocal to rotary; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention has for its object to provide a cheap and simple means whereby either a continuous rotary or a reciprocating motion may be obtained and imparted to various classes of machinery, and a rotary reverse motion obtained at the same time from a single piston, the dead-center overcome, and the motion retarded or accelerated by the application of interchangeable wheels upon the same journals and piston. These objects I accomplish by the means shown and illustrated in the accompanying drawings, in which—

Figure 1 is a representation of a plan view 30 of my invention with the fly or three-pointed cam wheel and piston removed. Fig. 2 is a view of the piston detached, and Fig. 3 is a view of the three-pointed cam-wheel detached.

Referring by letter to the drawings, A indicates a frame, to which are secured the axles a, on which the wheels are journaled.

B indicates the wheel, which I preferably place upon the forward journal. This wheel 40 has one of its faces provided with a waved or convoluted cam-groove, the center of which represents in outline a five-pointed star having its radial arms slightly curved outwardly and lateral to a pointed terminal forming the inner walls of the groove in which travel the two forward pins of the piston. The reverse wheel C, which I place upon the rear journal, has the outer walls of the groove oblique and semicircular alternately, as shown, with the 45 arms of the star conforming in outline there-

to, so as to have the walls of both parallel with relation to each other for the free and easy passage of the piston between them. D indicates the piston, which is provided with two elongated vertical slots, b b, for the passage of the wheel-journals, respectively. This piston is provided with vertical pins c c and c' c', which project from the opposite sides thereof, to respectively engage the grooves of the wheels, the two forward pins being on the 55 same horizontal plane, while the two rear pins are arranged, respectively, on a line, or nearly so, with the longitudinal walls of the rear elongated slot. By this arrangement of the pins upon the piston, when the wheels are 60 placed upon the journals, as before described, and the said pins brought in engagement with the grooves of the wheels from one side and power applied to the piston, both wheels will be driven in the same direction; but by removing the piston and reversing it upon the 65 wheels, so as to change the rear pins with relation to the grooves of the rear wheels, the forward wheel will be driven in the same rotary direction, while the rear one will take a 70 reverse movement.

In some cases I use a third wheel, which may have a three-pointed cam-groove, and may be placed upon the journal of one of the other wheels; and, if desired, a fourth wheel 75 may be used on the journal of the other wheel.

I do not wish to be understood, however, as confining myself to any number of wheels or points in their grooves, as a greater or less number may be employed, according to the 80 nature of the machine to be operated and the movement required.

This invention will be found particularly valuable in mowing-machines for driving the cutting apparatus, as a continuous reciprocating motion may be obtained with but little power. It may also be successfully applied to locomotive-engines for operating their drive-wheels, and to various other machines with a 85 beneficial result.

Having thus described my invention, what I claim as new, and desire to secure by Letters Patent, is—

1. The combination, with one or more cam-wheels, of a piston having pins arranged upon 90

opposite sides for engaging the cams, and elongated slots for the passage of the journals, substantially as and for the purposes specified.

2. The combination, with two or more cam-wheels having laterally-projecting journals, of a piston having pins for engaging the cams, so arranged as to overcome the dead-center and drive two or more wheels in opposite directions, substantially as specified.

In testimony whereof I affix my signature in the presence of two witnesses.

IRVING LEWIS HAWKINS.
